ADJUSTABLE PLIERS

Homer A. Mead, Turlock, Calif.

Application December 27, 1948, Serial No. 67,400

2 Claims. (Cl. 81—44)

1

This invention relates to, and it is an object to provide, improved pliers of adjustable, compound leverage type.

Another object of the invention is to provide pliers, as above, which include an improved adjustment assembly; the latter being designed for ease and convenience of close, ready, and effective adjustment of said pliers.

A further object of the invention is to provide pliers wherein the adjustment assembly is of such novel design as to maintain the handles in proper working position in any position of adjustment of said pliers; such handles, when the pliers are closed, always being apart at their free ends whereby to prevent pinching of the operator's hand.

An additional object of the invention is to provide pliers which have a greater grip, or leverage on the jaws, when the pliers are adjusted for relatively small work; this result being accomplished through the medium of the aforesaid novel adjusting assembly.

A still further object of the invention is to provide pliers which are constructed in a compact manner; the pliers being relatively thin and not of undue width.

It is also an object of the invention to provide pliers designed to minimize friction between the working parts, and to thereby reduce wear.

Still another object of the invention is to provide pliers which include cooperating jaws having flat, overlapping shanks pivoted together at their inner ends, there being a handle projecting from one shank only, and a separate cooperating handle having an adjustment plate engaged between said shanks and adjustably pivoted to the latter in a novel manner. This pivoting arrangement includes a pair of longitudinally spaced pins projecting from opposite sides of said adjustment plate into slots in corresponding shanks; the slot in said one shank being diagonal thereof and notched for adjustable engagement by the corresponding pin, and the slot in the other shank being lengthwise thereof and engaged in fulcrum relation by its corresponding pin.

A further object of the invention is to provide pliers designed for ease and economy of manufacture.

Another object of the invention is to provide practical and reliable pliers, and ones which will be exceedingly effective for the purpose for which they are designed.

These objects are accomplished by means of such structure and relative arrangement of parts as will fully appear by a perusal of the following specification and claims.

In the drawings:

Fig. 1 is an elevation of the pliers, in one adjusted position and with the handles closed, taken from the side to which the adjusting slot opens.

2

Fig. 2 is a similar view, but is taken from the opposite side of the pliers; the adjacent handle being broken away.

Fig. 3 is a fragmentary elevation, with the pliers set as in Fig. 1, but with the handles partly opened.

Fig. 4 is a fragmentary elevation showing the pliers set for full closing of the jaws.

Fig. 5 is a fragmentary elevation of the pliers with the handles full apart for adjustment of the jaw setting.

Fig. 6 is a fragmentary edge elevation of the pliers.

In Figs. 1-5, inclusive, the retention nuts have been omitted from the pins for the purpose of clarity.

Referring now more particularly to the characters of reference on the drawings, the improved pliers comprise a pair of cooperating jaws 1 and 2 having adjacent serrated working faces 3.

The jaws 1 and 2 are formed with integral, flat shanks 4 and 5 disposed in generally overlapping relation; said shanks 4 and 5 being in parallel but spaced apart relation by reason of the structural arrangement hereinafter described.

At its inner end the shank 4 includes a boss 6 which bears against the other shank; such shanks being pivoted together through the boss, as at 7.

The shank 4 merges rearwardly of the pivot 7 into an integral handle 8; the other and cooperating handle of the pliers being indicated at 9.

Such other handle 9 is formed, at its forward end portion, with a flat, elongated adjustment plate 10 which is engaged, in face to face relation, between the flat shanks 4 and 5.

The flat, elongated adjustment plate 10 is fitted, at its forward end portion, with a pair of fixed, longitudinally spaced pins 11 and 12 which project laterally outwardly from opposite sides of said adjustment plate. The pin 11 may be termed the adjustment pin, while the pin 12 may be termed the fulcrum pin.

The adjustment pin 11 projects through an elongated adjustment slot 13 formed in the shank 4 in diagonal relation to the longitudinal median line of said shank, while the fulcrum pin 12 projects through an elongated fulcrum slot 14 formed in the shank 5 lengthwise of, and substantially on, the longitudinal median line of the latter.

With the above arrangement it will be noted that in all adjusted positions of the parts of the pliers, the slots 13 and 14 are generally in intersecting relation to each other.

The outer longitudinal edge of the adjustment slot 13 comprises a row of substantially semi-circular notches 15; the adjustment pin 11 normally bearing in one of said notches 15, but being square sided, as at 16, so that when rotated a part circle and freed from said notch, such pin may be moved lengthwise of the slot 13 for engagement

in another one of said notches 15. Such adjustment is accomplished by swinging the handle 9 to a position projecting laterally of the tool, as in Fig. 5, at which time the square side 16 of pin 11 will bear against, and ride along, the straight inner edge of the adjustment slot 13. In this manner the adjustment pin 11 can be readily and conveniently changed from one notch 15 to another.

The pins 11 and 12 are fitted, on their outer ends, with retention nuts 17, which are only sufficiently tight to maintain the proper relationship of the parts, without causing frictional binding.

The adjustment pin 11 is selectively set in the notches 15 for the purpose of adjusting the spacing of the jaws 1 and 2 of the pliers; the design of the adjusting assembly including the pins 11 and 12 working in the slots 13 and 14, respectively, being such that in any position of adjustment of said pliers the handles 8 and 9 assume substantially the same working positions. Additionally, in any position of adjustment the handles 8 and 9, when fully closed, remain apart at their free ends whereby to not pinch the operator's hand; the adjacent portion of the adjustment plate 10 having a diagonal edge E which abuts against the boss 6, as in Fig. 2.

As the adjustment plate 10 moves to different positions of adjustment, the diagonal edge E rests at a new position on the boss 6 adjacent pivot 1 holding the ends of the handles the desired distance apart; the diagonal edge of the adjustment plate extending in generally the same direction and working in corresponding relation to the diagonal adjusting slot 13.

By reason of the generally intersecting relationship of the slots 13 and 14, with such slots extending in the respective shanks in the directions previously described, the pins 11 and 12 work in the slots to provide a most effective leverage, or working pressure of the jaws, when the handles 8 and 9 are moved relatively toward each other.

In any position of adjustment of the pliers the pin 11 tends to work into the related notch 15 so as not to drag the opposite side of the slot 13; this preventing any possible binding, and minimizing wear and friction. It should also be noted that by reason of the particular slot and pin assembly the pin 12 tends to roll rather than slide in the slot 14 when the handles 8 and 9 are moved together or apart relative to each other. Here again is a beneficial feature in the reduction of working friction, and the minimization of wear.

Another advantageous feature of the described pliers resides in the fact that when the pliers are adjusted for engagement of the jaws 1 and 2 with relatively smaller work, the gripping leverage is increased; this being by reason of the fact that the pins 11 and 12 are then closer to said jaws than otherwise. See Fig. 4.

The pliers as described above are a very practical and convenient tool; the adjustment of the jaws being accomplished by ready and easy manipulation of the handle 9 relative to handle 8. When in any adjusted position the leverage is compounded by the pin and slot arrangement so that there is forceful action of the jaws 1 and 2 against the work upon relative approaching motion of said handles 8 and 9; there being no tendency of the adjustment mechanism to slip or release when the pliers are in action.

From the foregoing description it will be readily seen that there has been produced such a device

as substantially fulfills the objects of the invention as set forth herein.

While this specification sets forth in detail the present and preferred construction of the device, still in practice such deviations therefrom may be resorted to as do not form a departure from the spirit of the invention, as defined by the appended claims.

Having thus described the invention, the following is claimed as new and useful, and upon which Letters Patent are desired:

1. A pliers comprising a pair of cooperating jaws, a shank integral with one jaw depending therefrom, a handle integral with the shank and depending therefrom, a shank integral with the other jaw and depending therefrom in spaced relation to the first named shank, a fixed-position pivot connecting the shanks at their lower end, another handle opposed to said first named handle, a plate rigid with said other handle and projecting between the shanks, the first shank having a longitudinal slot diagonal to the working face of the corresponding jaw and sloping down and away from said face, the other shank having a longitudinal slot substantially parallel to the working face of the corresponding jaw, a pin turnably projecting from one side of the plate into and movable along the first named slot, and another pin turnably projecting from the other side of the plate into and movable along the other slot; the pins being spaced lengthwise of the plate with the first named pin nearest the jaws; there being means between the first named pin and the corresponding slot to releasably lock said pin in selected positions of adjustment along said corresponding slot.

2. A pliers comprising a pair of cooperating jaws, a shank integral with one jaw depending therefrom, a handle integral with the shank and depending therefrom, a shank integral with the other jaw and depending therefrom in spaced relation to the first named shank, a fixed-position pivot connecting the shanks at their lower end, another handle opposed to said first named handle, a plate rigid with said other handle and projecting between the shanks, both shanks having a longitudinal slot therein and the slot in the first named shank sloping downwardly and inwardly diagonal to the slot in the other shank, a pin turnably projecting from one side of the plate into and movable along the slot in the first named shank, and another pin turnably projecting from the other side of the plate into and movable along the slot in said other shank; the pins being spaced lengthwise of the plate with the first named pin nearest the jaws; there being means between one pin and the corresponding slot to releasably lock said pin in selected positions of adjustment along said corresponding slot.

HOMER A. MEAD.
